UNITED STATES PATENT OFFICE.

EDMUND G. CAMPBELL, OF ST. PAUL, MINNESOTA.

DESIGN FOR A TOWEL-DISPENSER.

43,297.

Specification for Design.

Patented Dec. 3, 1912.

Application filed August 13, 1912. Serial No. 714,902. Term of patent 7 years.

To all whom it may concern:

Be it known that I, EDMUND G. CAMPBELL, a citizen of the United States, residing at St. Paul, in the county of Ramsey, State of Minnesota, have invented a new, original, and ornamental Design for Towel - Dispensers, of which the following is a specification, reference being had to the accompanying drawing, forming a part thereof.

The figure is a perspective view showing my new design.

I claim:

The ornamental design for a towel dispenser, as shown.

EDMUND G. CAMPBELL.

In presence of—

GENEVIEVE E. SORENSEN,
CATHERINE H. REHFUSS.
